UNITED STATES PATENT OFFICE.

BJÖRN E. HAUGEN, OF HILLSBOROUGH, NORTH DAKOTA.

GRAIN ELEVATOR AND WEIGHER.

SPECIFICATION forming part of Letters Patent No. 540,052, dated May 28, 1895.

Application filed November 17, 1894. Serial No. 529,128. (No model.)

To all whom it may concern:

Be it known that I, BJÖRN E. HAUGEN, a citizen of the United States, and a resident of Hillsborough, in the county of Traill and State 5 of North Dakota, have invented certain new and useful Improvements in Grain Elevators and Weighers for Thrashing-Machines; and I do hereby declare that the following is a full, clear, and exact description of the invention, which will enable others skilled in the art to which it appertains to make and use the same, reference being had to the accompanying drawings, which form a part of this specification.

15 My invention relates to improvements in grain elevators and weighers for thrashing machines, of that class or character in which the grain as it comes from the separator is elevated and deposited in the weighers and 20 from thence dumped into a chute which conveys it to bags, wagons or other receptacles.

The object of the invention is to provide an improved construction of the same, whereby by the elevator when not in use may be tilted 25 over to the center of the thrashing machine so as to distribute the weight more evenly and uniformly; and also to provide an improved weighing mechanism which will automatically dump the grain received from the 30 elevator when a predetermined amount has been fed to the weighing mechanism.

The invention consists in the novel construction and combination of parts hereinafter fully described and claimed.

35 In the accompanying drawings, Figure 1 is a side view of a thrashing-machine, showing my improvements applied thereto. Fig. 2 is a longitudinal sectional view taken through the center of the elevator. Fig. 3 is a trans- 40 verse section of the same. Fig. 4 is a detail side elevation of the weighing mechanism. Fig. 5 is an end view of the elevator. Fig. 6 is a detail perspective view of the weighing cylinder.

45 In the said drawings the reference numeral 1 designates a thrashing machine of any ordinary or suitable construction, provided with the usual separator 2, for separating the grain from the chaff and dirt.

50 The numeral 3 designates the elevator or conveyer, made in two sections, an upper and a lower one, each consisting of two rectangu-

lar tubes 4 and 5. The upper ends of the tubes of the lower section are connected together by a transverse plate 6, which is connected with a beam 7, secured to the thrasher. The outer end of this beam is provided with a vertical standard or upright 8, which supports the outer end of an inclined beam 9, the inner end of which is secured to beam 7. 60 Secured to the meeting ends of said beam and standard is a bracket 10, in which is journaled a pulley 12, around which passes a rope 13. This rope is secured to a rod 14 secured to the tubes 4, and passes around a pulley 65 15 connected with beam 7, and its ends are secured to and wound in opposite directions upon a windlass 16, secured to the lower section of the elevator or conveyer. This windlass is provided with a crank 17 and a ratchet 70 wheel 18, with which engages a pawl 19.

The upper section of the elevator or conveyer is hinged or pivoted at 20, to the lower section, and the lower ends of tubes 4 overlap the upper ends of tubes 5. At its outer side 75 the upper section is provided with catches 21 with which engage spring hooks 23 secured to the lower section, which hooks are connected together by means of rope 24. The object 80 of these hooks and catches is to hold the upper section in a vertical position when in use.

The lower section of the elevator is provided with a curved base 25, which connects the lower ends of tubes 5 together, and is provided at one side with a hopper 26 with which 85 communicates a spout 27 leading to the separator 2. Journaled in this base is a shaft 28, provided with two flanged pulleys 29 over which pass endless belts or bands 30, provided with a series of buckets 31. These 90 belts or bands also pass over a flanged pulley 32 secured to a shaft 34 journaled in the sides of a cap 35 which connects the upper ends of tubes 4 together. This shaft is provided with a pulley 36, which is connected by means of 95 the belt 37 with a pulley 38 of the shaft of the separator.

The cap 35, at one side or end is provided with an extension 39, forming a chute which receives the grain elevated by the buckets 31, 100 and delivers it to the weighing mechanism. This weighing mechanism consists of a cylinder 40, divided centrally by means of a vertical partition 41 into two weighing chambers,

each provided with an opening 42 at the top to alternately receive the grain fed from the elevator, and an opening 43 at the lower end for the delivery of the grain after having been weighed. The lower ends of these chambers are closed by means of gravity-gates 45, hinged to the said cylinder, which gates are actuated to alternately open and close said openings, as hereinafter described. The ends 10 of the cylinder 40 are provided with studs 46, which are journaled in brackets 47 having upwardly extending arms 48, secured to the ends of a yoke or bail 49, which is pivoted at 50 to the upper elevator section. This yoke 15 is provided with a downwardly extending rod 51 passing through a guide-plate 52, secured to said section and provided with a number of removable weights 53. The inclined arms 54, of the brackets 47 are provided with trans- 20 verse rollers 55 with which the gravity-gates 45 are adapted to engage when the cylinder is oscillated, so as to close the openings in the bottom thereof. These arms are also pro- 25 vided with an open bottom-pan 56 by which the grain delivered from the weighing cham- 30 ber is guided into a spout or chute 57 below, which conveys the grain away from the machine.

One of the ends or heads 58, of the cylinder 35 40, is provided with an upwardly extending lug 59, which is adapted to engage with a roller 60, journaled on a stud 61, secured to the extension 39. Secured to the lower ends 40 of the said cylinder are lugs 62, through which pass rods 63, to which the gravity gates are 45 hinged or pivoted. These lugs project out- 50 wardly a short distance beyond the periphery of the cylinder and also serve as stops for the same by engaging with transverse rods 64 se- 55 cured to the bracket 47.

The operation is as follows: The grain as it 60 comes from the separator is conducted to the lower part of the elevator, from which it is conducted by the buckets and endless band 65 to the upper part thereof, from whence it falls into the chute 39. From this chute the grain falls into one of the weighing chambers, the gravity-gate of which, engaging with the roller 55, closes the opening in the lower end thereof. 70 When a sufficient quantity of grain has been fed to the weighing chamber to overcome the weight connected with the bail or yoke, the latter will tilt, disengaging the lug 59 from the roller 60, and allowing the cylinder to 75 turn or rotate by reason of the weight of the grain contained therein, lugs 62 on the periphery of the cylinder engaging with one of the transverse rods 64 secured to the bracket 47, thus limiting the movement of the cylinder 80 and preventing it from turning too far. As the cylinder thus turns the pivoted gate of the chamber containing the grain will pass out of engagement with its roller 55, when the gate opens and the grain falls out of the said 85 chamber into the chute or spout below. As the yoke or bail is returned to normal position by its weight, the cylinder will be elevated

and the opposite side of the lug 59 will engage with the roller 60 so that the other weighing chamber will coincide or register with the chute 57 and its pivoted gate closed by its roller 55. The grain will now be delivered to this last-mentioned chamber until the weight of the yoke or bail is overcome, when the cylinder will again descend and rotate in the opposite direction to dump the load in the manner previously described. It will thus be seen that the weighing chambers will be alternately filled and discharged by the oscillation of the cylinder and the operation will be continuous, so long as sufficient grain is fed there- 90 to to overcome the weight of the yoke or bail.

When the elevator is not in use, the wind- 95 lass, see Fig. 3, is rotated to the left, causing the rope 13, on the left to be wound upon and the end at the right to be unwound from the windlass. This will cause the rope at the left of shaft 14 to be unwound therefrom and the slack at the right from the windlass to be wound thereupon, causing the upper section 100 of the elevator to be tilted over on the thrasher. A reverse movement of the windlass will return the elevator to normal position.

Having thus fully described my invention, what I claim is—

1. In a grain elevating mechanism for thrashing machines, the combination with the elevator made in two sections, each section consisting of two parallel rectangular tubes, the lower ones being connected together by a base and the upper ones by a cap, and the meeting edges overlapping each other and hinged together, the shafts journaled in said base and cap, respectively, the wheels secured thereto, and the endless band or belt passing around said wheels and provided with buckets, of the transverse shaft journaled to said upper section below the cap, the beam and standard for supporting the lower section, the windlass, the shafts provided with pulleys, and the rope wound upon said transverse shaft journaled to the upper section and upon the windlass, in opposite directions and secured to the windlass, substantially as described.

2. In a thrashing machine, the combination with the elevator having a delivery chute at its upper end, provided with a roller, of the bail pivoted to the elevator and provided at one end with a depending rod having removable weights thereon, the brackets pivoted to said bail and provided with an open bottom pan, the weighing cylinder journaled to said brackets and provided with a lug adapted to engage with said roller, the partition dividing said cylinder into two chambers, there being openings at top and bottom on opposite sides of said partition, the hinged gravity gates at the lower side of said cylinder, and the transverse rollers secured to the said pan, with which said gates are adapted to alternately engage, substantially as described.

3. In a thrashing machine, the combination with the elevator having a delivery chute at

its upper end provided with a roller 60, of the bail pivoted to the elevator and having at one end a depending rod 52, provided with removable weights, the brackets 47 pivoted to said bail and provided with an open bottom pan 56, the weighing cylinder 40 journaled to said brackets and provided with a lug adapted to engage with said roller, the partition dividing said cylinder into two chambers there 5
10 being openings at top and bottom on opposite sides of said partition, the hinged gravity gates 45, the lugs 62 secured to said cylinder and the rods 63 passing therethrough with

which said gates are connected, the transverse rollers 55 secured to the said pan with 15 which said gates engage, and the transverse rods 64 secured to the pan with which said lugs engage to limit the movement of the cylinder, substantially as described.

In testimony that I claim the foregoing as 20 my own I have hereunto affixed my signature in presence of two witnesses.

BJÖRN E. HAUGEN.
